ROAD GRADER

Franklin E. Arndt, Galion, Ohio, assignor to The
Galion Iron Works and Manufacturing Com-
pany, a corporation of Ohio

Application December 13, 1932, Serial No. 646,997

24 Claims. (Cl. 37—156)

My invention relates to road graders and one of the objects is the provision of improved and efficient means for increasing the extent of adjustment of the mold board while in horizontal 5 position.

A further object of the invention is the provision of improved and efficient means for adjusting the mold board to a bank-sloping position and holding the same in such adjusted position 10 during operation.

More particularly it is the object of the present invention to provide adjustable connections between the rear end of the drawbar and the rear portion of the supporting frame, which 15 may be adjusted in angular positions relative to the drawbar and moved laterally to adjust the lateral position of the mold board.

Other objects of the invention will appear hereinafter, the novel features and combinations, 20 being set forth in the appended claims.

In the accompanying drawings:

Fig. 1 is an elevational view of the road grader embodying my invention;

Fig. 2 is an enlarged elevational view of a 25 portion of the structure shown in Fig. 1;

Fig. 3 is a perspective view of the road grader with the mold board adjusted in high-lift or bank-sloping position;

Fig. 4 is a plan view of the connections be- 30 tween the rear end of the drawbar and the rear portion of the supporting frame;

And Fig. 5 is a sectional view of the rear portion of the road grader with only those parts included to show the positions of the mold board 35 and hangers relative to the spaced-apart supporting beams of the machine frame.

In Fig. 1 the portable frame 6 is shown mounted on the forward wheels 7 and the rear 40 wheels 8. The usual steering mechanism is shown at 9 and is connected by the rods 10, 10 to the steering wheel 11.

The supporting frame 6 is a rigid structure comprising spaced-apart channel irons 12, 12 as 45 shown in Fig. 5. Underneath the frame 6 is mounted the drawbar 13 the forward end of which is pivoted at 14 to the frame of the machine. The drawbar 13 supports the usual semi-circle 15 which adjustably carries the mold board 16 as shown in Fig. 2. The semi-circle 15 together with the mold board 16 may be rotated 50 on a vertical axis relative to the drawbar 13 by means of the wheel 17 and the connections 17' between the same and the circle-rotating mechanism shown in dotted lines at 18 in Fig. 2. By means of a pull handle 19 the rod 20 may be actuated to release the locking mechanism shown in dotted lines at 21 in Fig. 2 while the circle is being rotated. Upon release of the pull handle 55 20 the circle 15 and the mold board 16 may be held

at an adjusted angle in horizontal position relative to the road surface.

Mounted upon the frame 6 is a cross-piece 22 to the ends of which are secured at 23 and 24 bearings for the longitudinal horizontal shafts 25, 26 the rear ends of which are connected by means of worm gearing in the casings 27 and 28 to the spaced-apart vertical wheels 29, 30 which are mounted to rotate on horizontal axes in convenient position relative to the operator's 10 platform 31.

The forward ends of the longitudinal horizontal rods 25 and 26 are provided with crank arms 32, 33. These crank arms are connected by universal joints 34, 35 to the hangers 36, 37 each of which is provided with a rod 38 slidable into a pipe 39. A clamp is provided at 40 and includes a bolt for securing the sections 38 and 39 of the hanger rigidly in adjusted position. Furthermore, a pin may be inserted through holes 41 on opposite sides of the pipe 39 and a registering hole 42 in the rod 38, to absolutely prevent the rod 38 from sliding relatively to the pipe 39 after the parts have been adjusted.

The lower ends of the extensible hangers 36 and 37 are connected by means of the universal joints 43 and 44 to the cross-piece 45 which is rigidly secured to the rear end of the drawbar 13. It will thus be seen that the hangers 36 and 37 occupy vertical positions at opposite sides of the frame 6 when the mold board is in a horizontal position. Counterbalancing springs may be connected to the channel beams 12, 12 and to rotating sectors 46, 47 respectively rigidly secured to the longitudinal rockshafts 25, 26.

The above described apparatus including the steering mechanism, the pivoted drawbar, the mold board and semi-circle and the means for adjusting the same may be of well-known construction but as will be herein after more fully explained the hangers are improved as to their being individually extensible and locked in adjusted position combined with universal joints at their ends and mounted in relation to the channel beams 12, 12 so as not to be interfered with thereby when the mold board is moved to its high-lift or bank-sloping position shown in Fig. 5. Such improved hangers also co-operate with the connections between the rear end of the drawbar and the rear portion of the supporting frame 6 as explained hereinafter.

Pivoted to brackets 48, 48 extending rearwardly from the cross-piece 45 on the rear end of the drawbar 13 is a member 49 comprising a semi-circular plate 50 and a transverse cross-piece 51. The rearwardly extending arms 52 are pivoted at 53, 53 to the brackets 48 on a horizontal axis extending transversely of the rear end of the drawbar 13 and in the horizontal plane of the rear portion of this drawbar.

Pivoted on a vertical axis at 54 to the cross-piece 51 is a plate 55 having reinforcing webs 56, 56 at its longitudinal edges. Intermediate the ends of the plate 55 is a hole for receiving a pin 5 or a bolt 57 which hole is adapted to register with anyone of the holes 58, 58 in the semi-circular plate 50.

The outer end of the plate 55 is provided with a longitudinal socket 59 for receiving the sliding 10 rod 60 the rear end of which is pivoted on an upright axis 61 to the clevis 62 which in turn is pivoted on a horizontal axis at 63 to the laterally travelling support 64.

Mounted on the spaced-apart channel beams 15 12, 12 is a cross-piece 65 which carries a transverse plate 66 which serves to guide the carrier 64 transversely of the machine frame. By means of a rod 67 operable by the operator on the platform 31 are bevel gears 68 which are adapted to 20 rotate the screw-threaded rod 69 the ends of which are mounted in the bearings 70, 70. The screw-threaded rod 69 is threaded through the carrier 64 so that when the shaft 67 is rotated and the bolt or pin at 57 is removed the plate 55 25 may be swung laterally on the upright pivot 54. It can readily be seen that when the plate 55 is thus swung on the pivot 54 to an angular position relative to the line of draft of the road grader the plate 55 may be locked to the semi-circular plate 50 in such angular position. For 30 instance, if the carrier 64 is moved to one of the extreme ends of the screw-threaded rod 69 the bolt 57 may be used to secure the plate 55 in the outermost hole 58. Then upon returning the 35 carrier 64 in the opposite direction and moving the same to the other extreme end of the screw-threaded rod 69 the mold board may be shifted laterally to a greater extent than when a connection confined to the line of draft is operated 40 by such a screw-threaded rod.

When the bolt 57 is released the upright pivot 54 and the horizontal pivots 53 constitute a universal joint between the rear end of the drawbar 13 and the member 55. The rear end of the 45 member 55 has a sliding connection with the rod 60 and the rear end of the rod 60 is connected by a universal joint to the carrier 64. It will thus be seen that the connection between the rear end of the drawbar and the frame of the 50 machine is extensible by reason of the rod 60 in the socket 59 and the ends of this connection are provided with universal joints respectively at the rear end of the drawbar and the transverse guide 66.

55 By referring to Fig. 2 it will be seen that a securing plate 71 is riveted at 72 to the under side of the plate 55 and is provided with holes at its ends to receive the bolts 54 and 57. Consequently, since the plate 55 is on the upper side of the 60 semi-circle 50 and the rear end of the plate 71 is on the under side thereof, the plate 55 is confined to adjustment arcuately on the pivot 54 and cannot be moved away from the plate 50.

With the parts arranged as shown in Fig. 4 65 the mold board will occupy a central position relative to the road surface and may be angularly adjusted by means of the semi-circle 15. By operating the hangers individually by means of the wheels 29 and 30 the rear end of the drawbar 70 may be adjusted in elevation and lateral inclination and when such adjustment is made the brackets 48 are varied in elevation relative to the arms 52 on the pivots 53. The rear end of the rod 60 may swing on the horizontal axis 63 75 and the rod 60 may move into the socket 59 dur-

ing such adjustment of the mold board by means of the hangers 36, 37.

Not only do the adjustments shown in Fig. 4 including the angular adjustment of the plate 55 relative to the semi-circle 50, increase the extent to which the mold board may be shifted laterally by means of the screw-threaded rod 69 but such adjustments also increase the height to which the mold board may be lifted to one side of the machine or the other side thereof for 10 operation on sloping banks. Such bank-sloping position of the mold board is illustrated in Fig. 3.

When the mold board is to be moved to its bank-sloping position it is preferred to first 15 secure the plate 55 in an angular position remote from that side to which the mold board is to be moved. The plate 55 is then secured to the semi-circle 50 and the screw-threaded rod 69 operated to shift laterally the rear end of the drawbar to a maximum extent while the mold board is still in an approximately horizontal plane. The drawbar is then in a lateral position relative to the line of draft and the plate 55 being bolted to the semi-circle 50 will compel the drawbar to move along a conical path upon operating the 20 hangers by rotation of the crank arms 32, 33 to the position shown in Fig. 5. The rear end of the drawbar will then be at a higher elevation than its forward end. In order to facilitate ample 25 clearance of the mold board relative to the road surface during movement of the mold board to a bank-sloping position the lateral shifting mechanism shown in Fig. 4 and the crank arms 32, 33 shown in Fig. 5 may be individually operated 30 and whenever desired the hangers 36 and 37 may be extended or contracted and secured in adjusted positions. When the mold board has reached its bank-sloping position shown in Figs. 3 and 5 the angular relation between the plate 35 55 and the drawbar will be such as to afford 40 means to assist the hangers 36, 37 in rigidly supporting the drawbar in adjusted bank-sloping position. The crank arms 32, 33 are locked by the worm gearing in the casings 27 and 28 and the 45 hangers themselves are locked by the clamps at 40 and the pins in the holes 41, 42. The pivot 54 occupies such an elevation as to cause the plate 55 to slope downwardly toward the carrier 64; consequently, notwithstanding the sliding 50 connection at 59, 60, the bolt 57 is effective in holding the plate 55 in its angular position relative to the drawbar. Therefore, this angular 55 locked relation assists in holding the mold board against movement either up or down during operation in bank-sloping position.

It should also be noted that the range of adjustment in elevation is increased by having the hangers 36 and 37 extensible in length. Furthermore the extent to which the mold board may be shifted laterally while parallel to the road surface 60 may also be increased by extending the lengths of the hangers. However, it is most important to have the hangers extensible in length so that the upper one may be relatively short while the lower one is relatively long when the mold board is in bank-sloping position as shown in Fig. 5. During operation in bank-sloping position the lateral pressure on the cutting blade is resisted by the hangers and such resistance is made more effective by reason of the fact that the members 38 and 39 are telescopically related and clamped or locked in relative adjusted positions so as to hold them rigidly in alignment with each other.

It should also be noted that when the member 56 is moved from its position shown in Fig. 4 75

to such an angular position and locked there, that the outer edge of the circle 15 will be more elevated, and the outer end of the mold-board will also be elevated. The structure shown in Fig. 4 is pivoted to the rear end of the drawbar on an axis which extends horizontally and transversely when the mold-board is parallel to the road surface. When the outer edge of the circle is shifted upwardly to its maximum extent, the mold-board 10 may be rotated by means of the circle so that its outer end will be at an increased elevated position. The mold-board may thus be adjusted to a steep angle both when viewed sidewise and when viewed endwise of the machine, and the mold-board 15 may also cut along a steep bank. During such operation the rigid structure shown in Fig. 4, while being extensible during adjustments, serves to cooperate with the drawbar to form an arched support for the circle and the mold-board. 20 The drawbar and the structure shown in Fig. 4 are connected to the vehicle frame 12 at the forward and rear portions thereof and in addition thereto the drawbar is connected to the vehicle frame by means of the hangers 36 and 37. The 25 forces resisting deep cuts into the sloping bank are therefore distributed over the end portions and side portions of the vehicle frame, thus enabling the mold-board to very efficiently cut large amounts of material from the steep sloping 30 banks.

Obviously those skilled in the art may make various changes in the details and arrangement of parts without departing from the spirit and scope of the invention as defined by the claims 35 hereto appended, and I wish therefore not to be restricted to the precise construction herein disclosed.

Having thus described and shown an embodiment of my invention, what I desire to secure 40 by Letters Patent of the United States is:

1. In a road grader, the combination with a wheel supported frame, of a drawbar pivotally connected at its forward end to said frame, a mold board adjustably carried by said drawbar, 45 means for lifting the rear end of said drawbar, a support pivoted to the rear end of said drawbar on an axis extending transversely of the road grader, a member pivoted at one end to said support on an axis at right angles to the axis 50 of said support, means for locking said member at an adjusted angle relative to said support, a rod pivotally connected at its rear end to the rear portion of said frame, and means connecting said rod and member for relative sliding 55 movement only.

2. In a road grader, a frame, a mold board, a drawbar having its front end connected to said frame, means for adjusting the rear end of said drawbar vertically relative to said frame, a part 60 mounted on said frame for transverse movement in rear of said drawbar, a member pivotally connected to said drawbar on an axis located in the plane of the drawbar, a second member pivotally 65 connected to said first member on an axis generally perpendicular to the axis of the connection between said first member and said drawbar, and a third member longitudinally slid able in said second member, extending rearwardly therefrom, 70 and having its rear end connected to said transversely slid able part.

3. In a road grader, a frame, a mold board, a drawbar having its front end connected to said frame, means for adjusting the rear end of said drawbar vertically relative to said frame, a part 75

mounted on said frame for transverse movement in rear of said drawbar, a member connected to said drawbar for pivotal movement about two axes at an angle to each other, means for holding said member in any one of a plurality of different angular positions of adjustment about one of said axes, and a second member longitudinally slid able in the first-named member and connected to said transversely movable part. 5

4. In a road grader, a frame, a mold board, a drawbar having its front end connected to said frame, means for adjusting the rear end of said drawbar vertically relative to said frame, a part 10 mounted on said frame for transverse movement in rear of said drawbar, a member connected to said transversely movable part, a second member pivotally connected to said drawbar, provisions guiding said two members for relative rectilinear sliding movement, and means for varying the angle between the axis of pivotal connection 15 of the first-named member and the direction in which said two members are relatively slid able. 20

5. In a road grader, a frame, a mold board, a drawbar having its front end connected to said frame, means for adjusting the rear end of said drawbar vertically relative to said frame, a part 25 mounted on said frame for transverse movement in rear of said drawbar, and means interconnecting said drawbar with said transversely movable part, said means including a member having a universal connection with said drawbar, and adjustable means for limiting relative movement of said drawbar and member to pivotal movement about a single axis. 30

6. In a road grader, the combination with a frame, of a drawbar pivotally connected at its forward end to said frame, a mold-board carried by said drawbar, a support pivotally connected to the rear end of said drawbar on a transverse axis, a link pivoted to said support on an axis 40 extending transversely of said transverse axis, means for securing said link in adjusted angular position relative to said support, laterally shifting mechanism carried by said frame, and an operating connection between said laterally shifting mechanism and the rear end of said link. 45

7. In a road grader, the combination with a frame, of a drawbar pivoted at its forward end to said frame, means comprising spaced hangers for adjusting the elevation of said mold-board and 50 its inclination relative to the vertical, a support pivotally connected to the rear end of said drawbar on a transverse axis, a rearward extension from said support in lateral angular relation to the drawbar, and laterally shifting mechanism 55 mounted on said frame and connected to the rear end of said angular extension.

8. In a road grader, the combination with a portable frame, of a drawbar pivoted at its forward end to said frame, a mold-board mounted 60 on said drawbar, transverse shifting mechanism on the rear portion of said frame, a jointed connection between the rear end of said drawbar and said shifting mechanism, said jointed connection comprising an extensible link pivoted at its ends on parallel axes with a telescopic sliding connection between the pivots, and means 65 associated with said link intermediate the ends thereof for locking the jointed connection at an adjusted angle relative to the drawbar. 70

9. In a road grader, the combination with a portable frame, of a drawbar pivoted at its forward end to said frame, a mold-board mounted 75 on said drawbar, shifting mechanism comprising

a transversely extending rotary screw mounted on said frame rearwardly of said drawbar, means comprising a link pivotally connected at its rear end to said shifting mechanism and pivotally connected at its forward end to said drawbar, and mechanism intermediate the ends of said link for locking the latter at an adjusted angle relative to said drawbar.

10. In a road-working machine, the combination with a frame, of a drawbar pivotally connected at its forward end to said frame, a road-working implement carried by said drawbar, transverse shifting mechanism mounted on said frame and comprising a transverse screw threaded through a traveling nut, an extensible link pivoted at its rear end to said nut and pivotally connected at its forward end to said drawbar, said link comprising a telescopic sliding connection intermediate its ends, and mechanism comprising an arcuate support intermediate the ends of said link for locking the latter at an adjusted angle relative to the drawbar.

11. In a road-working machine, the combination with a frame, of a drawbar flexibly connected at its forward end to said frame, a road-working implement carried by said drawbar, a link member pivotally connected to said drawbar, mechanism connected to said link to adjust the same on its pivotal connection to said drawbar to various angular positions relative to the line of draft of the machine, and means for locking said link in adjusted angular relation to the drawbar.

12. In a road-working machine, the combination with a frame, of a drawbar flexibly connected at its forward end to said frame, transverse shifting mechanism comprising a transverse screw and a traveling nut, an extensible link pivotally connected at its rear end to said nut and pivotally connected at its forward end to the rear end of said drawbar, and releasable locking mechanism between the rear end of said drawbar and said link intermediate the ends of the latter to enable said shifting mechanism to swing said link on its forward pivot to either limit of angular adjustment in accordance with the limits of travel of said nut when said locking mechanism is released so that when the link is locked at either limit of angular adjustment, operation of the shifting mechanism will enable the rear end of said drawbar and the road-working implement carried thereby to be shifted laterally to its maximum extent while in road-grading position.

13. In a road-working machine, the combination with a vehicle, of a drawbar pivotally connected at its forward end to the forward end portion of said vehicle, a road-working implement carried by the rear portion of said drawbar, an arcuate support extending rearwardly from the rear end of said drawbar, transverse shifting mechanism on said frame rearwardly of said drawbar, an extensible link pivoted at its forward end to said arcuate support and pivoted at its rear end to said transverse shifting mechanism, and means for securing said link to said arcuate support in any one of a plurality of angular positions relative to said drawbar.

14. In a road-working machine, the combination with a frame, of a drawbar connected thereto, a road-working implement carried by said drawbar, mechanism comprising spaced-apart hangers for adjusting the elevation of the rear end of said drawbar together with said road-working implement, an arcuate support pivoted to the rear end of said drawbar on an axis extending transversely thereof, an extensible link pivoted

to said support on an axis extending transversely of said first-named support, mechanism for locking said link in adjusted relation to said arcuate support, and transverse shifting mechanism connected between the same frame and the rear end of said extensible link.

15. In a bank-cutting machine, the combination with a vehicle, of a drawbar pivotally connected at its forward end to said vehicle, a bank cutting implement carried by said drawbar, mechanism comprising extensible hangers for adjusting the elevation and inclination of the bank cutting implement relative of said vehicle, a support pivoted to the rear end of said drawbar on an axis extending horizontally and transversely of the path of travel of the machine when the said cutting implement is in road grading position, transverse shifting mechanism mounted on said vehicle rearwardly of said support, an extensible link pivotally connected at its forward end to said support and pivotally connected at its rear end to said shifting mechanism, and means for securing said link intermediate its ends to said support in any one of a plurality of angular positions to vary the extent of lateral shifting of the implement when in road grading position and to enable said implement to be moved to a relatively high bank-cutting position when one of said hangers is relatively short and the other relatively long.

16. In a road grader, the combination with a vehicle frame, of a drawbar pivotally connected at its front end to said frame, a mold-board carried by said drawbar, means comprising spaced-apart extensible supporting hangers for adjusting the elevation of the moldboard and the inclination thereof relative to the vertical, transverse laterally shifting mechanism carried by said vehicle frame, a link structure having a rear section and a forward section, a universal joint between the rear section and said transverse laterally shifting mechanism, a pivotal connection between the forward section and the rear end of said drawbar on an axis extending transversely of such drawbar parallel to the road surface when the moldboard is in horizontal road grading position, said link structure comprising a pivot between said sections on an axis extending transversely of the aforesaid transverse axis to afford relative adjustment between said sections, and means for securing said sections together to render said link structure inflexible relative to the drawbar in the plane of the latter.

17. In a road grader, the combination with a vehicle frame, of a drawbar connected at its forward end to said frame, a mold-board carried by said drawbar, transverse shifting mechanism on said frame rearwardly of said drawbar, connecting means between said shifting mechanism and the rear end of said drawbar comprising an extensible device pivoted at its ends on parallel axes, and mechanism intermediate the ends of said extensible device for locking the same against pivotal movement on its forward pivot.

18. In a road machine, the combination with a main frame, of a tool-supporting frame, a road working tool carried by said tool-supporting frame, a draft connection between said tool-supporting frame and said main frame, means to support the tool-supporting frame from the main frame comprising spaced hangers each adjustable in length, laterally shifting mechanism between said tool-supporting frame and said main frame including a train of co-operating pivotally connected members one of which comprises a

- movable rigid member having a plurality of fastening stations thereon and another of said members being extensible but rigid against lateral flexure and connectible to any selected one of 5 said fastening stations, said train of pivotally connected members extending rearwardly from the tool-supporting frame to the said main frame so as to be rigid against lateral flexing when the tool-supporting frame is in road-grading position, 10 such laterally shifting mechanism being adapted to co-operate with the hangers for positioning and maintaining the tool-supporting frame at an angle to one side of the main frame in bank-sloping position.
- 15 19. In a road grading machine, the combination with a vehicle frame, of a supplemental frame connected thereto, a road working implement carried by said supplemental frame, mechanism comprising spaced-apart hangers connected between said vehicle frame and said supplemental frame for effecting adjustment of the road-working implement in elevation and transverse inclination relative to the roadway, laterally shifting mechanism extending rearwardly 20 from said supplemental frame to said vehicle frame and comprising an extensible connection adapted to be adjusted to various angular relations to the longitudinal axis of said supplemental frame, such angular relation on one side 25 of the machine being opposite to that on the other side of the machine to afford a wide variation in the lateral shifting of the road-working implement from both sides of the machine, and mechanism for operating said laterally shifting mechanism from the vehicle frame after such angular 30 adjustments have been made.
- 20 20. In a roadworking machine, the combination with a vehicle frame, of a drawbar frame, a road working implement carried by said drawbar frame, a flexible connection between the forward end 35 of said drawbar frame and said vehicle frame, spaced-apart extensible hangers between said main frame and the rear portion of said drawbar frame, laterally shifting mechanism on the vehicle frame, extensible connecting mechanism extending longitudinally of the machine from the rear end of the drawbar frame to said laterally shifting mechanism, said extensible connecting mechanism being flexible on a horizontal transverse axis in response to the operation of the 40 hangers but rigid against lateral flexure to render effective the laterally shifting mechanism in effecting lateral adjustment of the road-working implement, said extensible connecting mechanism comprising members adapted to be adjusted 45 relatively to each other with one member in lateral angular relation to the drawbar with said members in triangular relation to the longitudinal axis of the machine, the construction and arrangement being such as to enable said hangers and the connections between the ends of the drawbar and the vehicle frame to serve as the sole support for the drawbar and the road-working implement and to enable the hangers when 50 extended to different lengths one relatively long and the other relatively short to effect movement of the road working implement to steep bank-cutting position at one side of the machine.
21. In a road grader, the combination with a vehicle frame, of a supplemental frame connected thereto, a grader blade mounted on said supplemental frame, spaced-apart hangers connecting 55 said frames, laterally shifting mechanism spaced rearwardly from the rear end of said supplemental frame, an extensible device connected to said laterally shifting mechanism and extending forwardly therefrom, mechanism connecting said extensible device to said supplemental frame in angular relation to the longitudinal axis thereof and to occupy an upwardly extending position when the grader blade is in steep bank-cutting position, and means for adjusting said hangers 60 in co-operation with said laterally shifting mechanism to effect adjustment of the grader blade to steep bank-cutting position, the construction and arrangement being such that when the grader blade is in steep bank-cutting position the upward slope of the said extensible device effects such elevation of the rear end of the supplemental frame as to position its axis to extend rearwardly substantially above said laterally shifting mechanism, such angular relation of said extensible 65 device effecting elevation of the supplemental frame while moving out from under the vehicle frame to one side thereby affording clearance of the heel of the blade from the road surface.
22. In a bank-cutting machine, the combination with a vehicle frame, of a drawbar flexibly connected at its forward end to the front end of said vehicle frame, spaced extensible hangers between said vehicle frame and said drawbar, a grader blade carried by said drawbar, laterally shifting mechanism on said vehicle frame spaced rearwardly from the rear end of said drawbar, a support pivotally connected to the rear end of said drawbar, an extensible device pivotally connected to said support and pivotally connected to said laterally shifting mechanism, mechanism securing said extensible device in adjusted angular relation to the longitudinal axis of said drawbar, and means for operating said hangers with one shorter than the other in co-operation with said laterally shifting mechanism to effect movement of said extensible device to an upwardly sloping position to secure positioning of the drawbar axis over and above the laterally shifting mechanism, such angular relation of said extensible device 40 securing elevation of the rear end of the drawbar as it moves out from under the vehicle frame to one side thereof.
23. In a road grader, the combination with a wheel supported frame, of a drawbar pivoted to the front portion of said frame, a moldboard adjustably carried by said drawbar, and adjustable connections extending from the rear end of said drawbar and longitudinally thereof to the rear portion of said frame, said connections comprising laterally spaced-apart attaching means respectively adjustable to occupy positions on opposite sides of the machine.
24. A road grading machine comprising the combination with supporting framework, of a road working implement and a drawbar carried by said framework, means spaced from the rear end of the drawbar longitudinally of the machine for shifting the drawbar and said road working implement laterally of the said framework, and adjustable connections extending rearwardly from said drawbar and longitudinally thereof to said shifting means and comprising laterally spaced-apart attaching means for enabling said drawbar to be supported on opposite sides of said frame.

FRANKLIN E. ARNDT.
